UNITED STATES PATENT OFFICE

BENJAMIN F. W. HEYER, OF BELLEVILLE, NEW JERSEY

DESIGN FOR A COMBINED CHARGING AND TESTING APPARATUS AND STOCK STAND

Application filed December 1, 1932. Serial No. 46,276. Term of patent 3½ years.

To all whom it may concern:

Be it known that I, BENJAMIN F. W. HEYER, a citizen of the United States, residing at Belleville, in the county of Essex, State of New Jersey, have invented a new, original, and ornamental Design for Combined Charging and Testing Apparatus and Stock Stand, of which the following is a specification, reference being had to the accompanying drawing, forming part thereof.

The figure is a perspective view of a combined charging and testing apparatus and stock stand, showing my new design.

I claim:

The ornamental design for a combined charging and testing apparatus and stock stand, as shown.

BENJAMIN F. W. HEYER.
